ACOUSTICAL TILE

Henry A. Sheehan, New York, N.Y., assignor to Allied Chemical Corporation, New York, N.Y., a corporation of New York

Filed Sept. 21, 1962, Ser. No. 71,797

Term of patent 14 years

(Cl. D18—2)

FIG. I.

FIG.2.

FIG.3

FIGURE 1 is a front perspective view of an imperforate acoustical tile showing my new design;

FIGURE 2 is a front perspective view of a perforate acoustical tile showing my new design; and

FIGURE 3 is an enlarged fragmentary cross-sectional view of FIGURE 2 taken on line 3-3 thereof.

I claim:

The ornamental design for an acoustical tile, substantially as shown and described.
